UNITED STATES PATENT OFFICE

JULIAN A. CAMPBELL, OF LONG BEACH, CALIFORNIA

ABSORBER

Application filed December 17, 1927. Serial No. 240,741.

This invention relates to devices commonly known as absorbers, or bubble towers, their function being to intimately distribute and admix gas or vapor with liquid so as to attain an intimate and finely divided contact with gas or vapor. In general, a function of such an apparatus is to establish a condition of vapor tension equilibrium between the liquids and vapors, and, consequently, such apparatus may be used, and are used, either for the purpose of absorbing liquids from gases or vapors, or for the purpose of cleaning liquids of entrained gases or vapors. Consequently, although I describe my invention as an absorber, used, for instance, to absorb entrained and vaporous liquids from natural gas, it will be understood that the invention is not limited to that particular use. The absorber described in the following detailed description has some similarity to the absorber set out in my prior application, Serial No. 123,417, filed July 19, 1926. Both these absorbers utilize a double perforated floor, the liquid being introduced into the space between the floors of a double set, and the gas flowing upwardly through both floors and through the space between them, forming a mass of froth in the space between floors and forcing the formed froth up through the perforations of the upper floor, the froth being broken up above the upper floor and the liquid being conducted to the next set of floors below, while the gas passes on up through the next set of floors above. In some of its aspects the present invention relates to improvements upon that type of absorber; but the present invention is not wholly restricted or limited to improvements upon that specific type of absorber, some of the improvements described in this present application being applicable to other types of absorbers, and further the present structural improvements providing the apparatus for a new method which is made specifically the subject matter of claims in a companion case entitled "Method of absorption", Serial No. 240,742, filed on even date herewith. However, for the purpose of clearly describing the specific and illustrative form of the

invention, that type of absorber having sets of double floors is here chosen.

A characteristic feature of the present invention, as compared with my previous absorber structures, resides in the method and structure for transferring the liquid from a point above one floor down to a point above a floor below. In my prior structures, as for instance in the prior application above referred to, this liquid transfer has been accomplished by having the liquid flow over the edges of pans and then flow down through tubes which lead down from the pans through the floor or floors immediately below and discharge the liquid above a floor below or between the two floors of the set next below. The present construction embodies an arrangement utilizing a double shell, the space between the two shells serving to pass the liquid downwardly stage by stage. The structure lends itself to attainment of simplicity of structure and assembly and the attainment of high efficiency. It obviates the necessity of liquid collecting pans and liquid delivery tubes and substitutes a new floor formation which facilitates collection of the liquid for delivery which, particularly in the double floor arrangement, attains very high efficiency. This last mentioned floor formation is also a characteristic improvement supplied by the present invention and has largely to do with the improvement in methods which is the subject matter of my said companion application.

In this apparatus application both the structure and method will be explained, in order to give a clear and full understanding of the inventions; but the claims here are directed to apparatus while those of the companion case are directed to method.

With these preliminary understandings, the invention will now be best understood from a detailed and specific description of a particular and illustrative form of apparatus embodying the invention, reference for this purpose being had to the accompanying drawings in which—

Fig. 1 is a fragmentary vertical central section of the absorber;

Figs. 2, 3, 4 and 5 are horizontal cross

100

sections taken respectively on lines 2—2, 3—3, 4—4, and 5—5 of Fig. 1;

Fig. 6 is a perspective of one of the inner shell sections;

Fig. 7 is a perspective of another of the inner shell sections;

Fig. 8 is an enlarged fragmentary vertical section in the nature of an enlargement of certain portions of Fig. 1.

- 10 In the drawings the numeral 10 designates an exterior shell which may be of any suitable form, usually cylindric and of a substantial height as compared with its diameter. Near the bottom of the shell there is a gas inlet 11 and a liquid outlet 12, the bottom of the shell usually containing a float 13 which acts to operate a valve controlling the liquid outlet (not shown, as it has no bearing on the present invention). Near the bottom of the shell 15 there is an internal ring 15 having an 20 standing inner flange 16 that forms an annular liquid holding channel around the periphery of the shell, for the purpose of forming a liquid seal at a point where the liquid 25 is finally discharged into the bottom part of the shell, all as will hereinafter appear. This ring 15 also forms the supporting shelf which supports the several inner shell sections and the several superposed floors.
- 30 Briefly described, the shell and floor structure is made up of a series of outer shell sections 20 and 20^a and a series of inner shell sections 21, 21^a and 21^b; with perforated floors 22 and 23, and an uppermost perforate 35 floor 24, supported and spaced by the several shell sections. The floors are preferably supported and spaced so that they are located in pairs, 22 and 23. The outer shell sections 20 and 20^a are all imperforate. Their function 40 being merely to form an outer shell wall for the passages which are located between such outer shell wall and the inner shell wall formed of sections 21 and 21^a. Operatively and functionally the outer shell sections 20 and 20^a may be regarded as the outer wall 45 of the double shell structure herein referred to, the outermost continuous shell 10 being provided only for the purpose of making the apparatus pressure-tight as a whole. Or the outermost continuous shell 10 may be looked 50 upon as the outer shell of the double walled structure, the outer shell sections 20 being provided merely to make a wall, outside of which the assembly bolts may be passed. It is convenient to run those assembly bolts 55 through the edges of the several floors, to hold the whole structure in aligned position, and it is also convenient to have the several floors extend their edges outwardly past the outer shell sections 20, 20^a, as thereby certain 60 perforations in the several floors, registering with the spaces between the shell sections, may be utilized for controlling and directing the flow of liquid. And it is convenient to 65 have the assembly bolts pass through the sev-

eral floors outside of the operating space between the double walls, as thereby it is not necessary to make tight joints where the bolts pass through the several floors. Consequently, in a preferred structure, in accordance with the present invention, the several floors 22 and 23 are of such diameters as to fit fairly snugly into the outermost main shell 10. The edges of these floors, outside the shell sections 20, have notches 25 which pass the vertical assembly bolts 26, and the outer shell sections 20, 20^a have circular ribs 20^b that, bearing against the bolts, serve to center these shell sections. The assembly bolts are secured at their lower ends to the ring 15 and, passing upwardly through the notched edges of all the floors, and also through the uppermost assembly ring 27, have nuts 28 at their upper ends, which, being screwed down on spacer tubes 29, compress the whole assembly tightly in a vertical direction and make sufficiently fluid-tight joints between the several floors and the edges of the several shell sections.

The construction of the shell section 21^a is 90 similar, with openings 35^a and ribs 36^a and 37^a, the only difference between sections 21 and 21^a being a matter of height.

Each upper floor 23 has one or more raised 95 perforated surfaces 43. In the particular design here shown these raised perforated surfaces 43 are formed as circular perforated plates raised on circular rims 44 above the surface of floor 23, each formation 43, 44, being in the form of an inverted pan with a 100 perforated top. These inverted pans are spaced apart from each other as shown in the various views so as to allow a considerable space around the pans for separated liquid to collect on the floor 23, the liquid collecting 105 until it reaches a height sufficient to flow out through the openings 35. Each floor 23 also has peripherally arranged perforations 45 extending around its complete periphery and in such positions as to register with the annular 110 space between the two concentric shell sections 20, 21 and 20^a to 21^a. Each lower floor 22 is preferably perforated over its entire 115 surface within the circle of the shell section 21^a, and outside the circle of that shell section 21^a it has perforations 46 extending around half of its periphery only, these perforations registering with a half-annular space between the shell sections 20, 21, and 20^a, 21^a. The several floors 22 and 23 and 120 the several shell sections 20, 21, 20^a and 21^a are all of identic construction, but are assembled in such a manner as to control and direct 125 the flow of liquids as will now be described. The uppermost inner shell section 21^b may be identic in structure with shell section 21, but is inverted, so that its openings 35^b come near its upper edge rather than near its lower edge.

In operation as an absorber it will be un 130

derstood that rich gas is fed under pressure into the lower end of shell 10, the gas passing upwardly through the several floors, and the denuded gas finally passing off through the gas outlet 50 at the top. At the same time, absorbing oil is being introduced through a suitable oil inlet, such as indicated at 51, the oil feeding through perforated distribution pipe 51^a out over the uppermost 5 perforated floor 24 and rising, as froth, to a level where the oil from broken froth overflows through openings 35^b of shell section 21^b. Flowing through these openings the oil flows into a half annular space between shell section 21^b and a corresponding concentric section 20, being restricted to that half annular space by the two ribs 37. The uppermost floor 24 has a semi-circular series of perforations 46^c similar to the perforations 46 of floors 22; and the oil flows downwardly through these perforations 46^c into the half annular space A immediately below and between the next lower shell sections 21 and 20. An absorber constructed in accordance with my invention may contain any suitable number of floor sets; but for the purpose of explanation, I will suppose that the upper set shown in Fig. 1 and in Fig. 8 is the uppermost set of the absorber. Thus, 10 the oil will first flow down through the half annular space A between shell sections 20 and 21, at the right-hand side of Figs. 1 and 8, and thence the oil will flow through the perforations 45 of floor 23 into the half annular space B between shell sections 20^a and 21^a and between floors 22 and 23. Thence the oil will flow directly through openings 35^a into the space C inside shell section 21^a and between the two floors 22 and 23. Here the oil, spreading out over floor 22, is picked up by the gas passing up through that perforated floor and a mass of froth is formed, this mass of froth rising and filling the inverted pans 43, 44 until the froth is forced up through the perforations in plates 43. The comparative aggregate perforation areas of floors 22 and 23 are preferably such that the velocities through the perforations are about equal. For instance, in an average case, the lower floor 22 has perforations $\frac{3}{2}''$ diameter on 1" spacings. The plates 43 of the upper floor have holes of the same diameter but on half inch spacings. The total area of plates 43 is about half of the total area of a floor 22; so that the aggregate perforation area of an upper floor 23 is about twice the aggregate perforation area of the lower floor 22. But the lower floor passes gas only, while the upper floor passes both gas and liquid; and in an average case the velocities through the two floors is consequently somewhat near equality. The action at and above the lower floor is to form a mass of froth, the oil being frothed as completely as possible. This mass of froth moves up under the gas pressure and

is forced through the upper floor perforations. At the upper floor perforations the froth bubbles are reduced to substantially uniform size, and any unfrothed gas and oil is formed into bubble formation. In other words, the first action at the upper plate perforations may be considered to be to make the froth more uniform, as a preliminary to disrupting the froth and atomizing the oil. The velocity through the perforations—the expansion of the gas above the perforations—breaks up the froth bubbles and forms the oil into an exceedingly fine mist floating in the gas above the upper floor. This mist falls through the gas, the collecting liquid flowing down below the pan tops to collect on the floor 23 around the pans. Thence the oil flows out through the openings 35 at the left-hand side of shell section 21 into the half annular space D (see Fig. 8) between that shell section and shell section 20. Here the oil flows down through floor perforations 45, through space E between shell sections 20^a and 21^a and floors 23 and 22, and thence the oil flows through the floor perforations 46 at the left-hand side of floor 22 and into and through the half-annular space A¹ between the next lower shell sections 20 and 21. Half-annular space A¹ is the same as half-annular space A except that it is arranged at the opposite side of the assembly. The oil flows directly downwardly through space A¹ and on down through floor perforations 45 into the left-hand half-annular space B¹ between the next lower shell sections 20^a and 21^a. Here the oil, stopped from further downward flow by part 22^a of floor 22, flows again through openings 35^a which, in this shell section 21^a, are arranged at the left of the apparatus as shown in the drawings, the oil flowing into the circular space C¹ inside shell 21^a between floors 22 and 23. The oil is here again subjected to the action of the upwardly flowing gas, the froth rising and being forced through perforated plates 43, the gas being freed to pass on up through the next perforated floor 22, and the atomized and collected oil flowing down around pan walls 44 onto floor 23, and thence out through opening 35, at the right-hand side of shell section 21, into and through the half-annular space D¹ at the right hand side of the assembly. Thence the oil flows down through floor perforations 45 and 46 and through right-hand half-annular space E¹, and into right-hand half annular space A². This space A² is an exact counterpart, both in structure and position, with the first mentioned half-annular space A; and the flow of the oil from here on down through the apparatus is repetitious of the flow now fully described. Upon leaving the last and lowermost floor set, the oil will pass through the openings 35 such as those shown at the lower left side of Fig. 1, and, passing through perforations 45 and 46 in

those lowermost floors, will pass thence into space F (see Fig. 1 at the lower left) outside the lowermost shell section 21. Thence the oil passes through openings 35 in that lowermost shell section 21, over the seal flange 16, and drops down into the body of oil which normally stands in the bottom of shell 10. This final passage of the oil is indicated by the arrows at the lower left-hand side of Fig. 1.

- 10 The oil being formed into a fine mist above each floor, falls out of the gas rather slowly. Consequently, in operating at reasonable gas flow velocity a certain amount of the mist, but not a large proportion, is carried up with the 15 gas through the next perforated floor 22 where it is merely caught by and merged in the froth being formed there. To prevent any oil mist being carried out of the apparatus above the uppermost floor 23 I have provided 20 the uppermost perforated floor 24 (which is like floors 22 but without any associated floor 23). The incoming oil is first distributed in a thin layer over floor 24. The gas rises through that layer, forming and raising a 25 mass of froth whose level rises to the lower edges of openings 35^b. At the upper froth surface, and at the opening edges which are preferably sharp, the froth breaks up, freeing the gas to pass on up and out outlet 50 as 30 substantially dry gas, the freed oil flowing through openings 35^b to pass down through the apparatus. As shown in the drawings, the upper floor is spaced considerably from the top of the shell, this being commonly done 35 in order that entrained liquid particles in the gas may drop back on said floor.

From what has been said it is now readily understood that the several floors and the several shell sections, with their respective openings and perforations, are so assembled that a passage is formed for the oil at one side of the structure from a point above an upper floor of one set directly down to a point between the two floors of the set next below. Then 45 the structural assembly is such that an oil passage is formed at the opposite side of the assembly to pass oil from above the upper floor of that next set below, directly down, past the upper floor of the next successive set below, into the space between two floors of that last mentioned next lower set. Such alternate passage of the oil down through the apparatus at opposite sides is kept up until the oil is finally discharged. The reason for 50 dividing the annular spaces into halves will now be seen. Considering any one upper floor 23, it will be seen that the oil first passes down through its perforations 45 at one side. Then the oil passes upwardly through the central parts of that floor in the form of froth. The resultantly freed oil, from the mist, must then again pass down through that same floor 23, and this it does by passing through the perforations 45 at the other side of that same 55 floor 23. The oil thus passes through each

floor 23 three different times, once inside the inner shell 21, and twice in the annular space outside that inner shell 21. To keep the two outside passages of oil separated, the annular space outside shell 21 is divided by ribs 37 70 into two half-annular spaces, as A and D, or A¹ and D¹. After the oil passes down last through a floor 23 it must then pass directly down through the floor 22 immediately beneath in order to pass on down through the 75 next floor 23. In doing this the oil must pass through the annular space between floors 23 and 22, outside shell 21^a, and this flow of oil must be kept separate from the previous flow of the oil through that same annular space at 80 the opposite side. For this reason said annular space is divided into two half-annular spaces, as B and E, or B¹ and E¹, by the dividing ribs 37^a.

It will be seen that in one aspect of this apparatus, the upper floor 23 of each set may be viewed merely as a perforated floor. The raised perforated surfaces are provided so that the froth will be delivered into the space above floor 23 without having to pass through the oil that is constantly accumulating over that floor; so that there is no further tendency to form froth but, on the contrary, an action to atomize the oil by breaking up the thin oil film of the previously formed froth. And 95 this has particularly to do with the characteristic features of my method. The operations are regulated so that the oil level never rises above the perforated plates 43, and the amount of unatomized oil froth above plates 43 is, in practice, found to be so small that neither it nor the oil, interferes with the atomizing action. Furthermore, the accumulated oil that flows on down to the next set is found 100 to be substantially wholly freed of gas. 105

Considering the paths of flow of the liquid oil through the apparatus, it will be seen that the oil, after flowing into space D, for instance, then flows down between the spaced shell sections and through spaces E and A¹ 110 and B¹ just as if the found spaces D, E, A¹ and B¹ formed one continuous space or passage; that is, the floors 23, 22 and 23 offer no obstruction to the flow of oil down through these spaces because the floors there are all 115 perforated. In other words, the flow of oil down through these spaces is precisely as if the floors 23 and 22 of the upper set, as shown in Fig. 8, and the floor 23 of the lower set in that figure, did not cross the annular space between the spaced shells. The only point where a horizontal obstruction of the half-annular space between the shells is necessary is at, or approximately at, the level of the next lower floor 22 (at the lower left-hand in Fig. 8, for the elements here under consideration). Thus, so far as functional operation is concerned, the extension of those three specified upper floors through the half-annular space at the left of Fig. 8 can be dis- 120 125 130

regarded; and the peripheral portion of the lowermost floor 22, marked 22^a in the lower left hand portion of Fig. 8, may be regarded broadly as any horizontal stop extending across the half-annular space at the lower left of Fig. 8. Thus in a broader aspect of my invention, the extension of the three said floors 23, 22 and 23 through said half-annular space may be disregarded, and the portion 22^a of the next lower floor 22 may be regarded merely as a horizontal stop. But in a more particular aspect of my invention it is advantageous that all of the floors extend through the half-annular spaces and be perforated, because thereby a very convenient and simple support for the several floors by the shell sections is attained, the said horizontal flow stop is provided in a very simple manner, and the design and construction of 20 the several floors, as well as the several shell sections, is standardized.

I claim:

1. In an apparatus of the character described, the combination of a double-walled shell with an annular space between the walls, a plurality of spaced superposed perforated floors within the inner wall, said inner wall having openings at one side above one floor and at the opposite side above the floor next below, and dividing ribs separating the space between the walls at one side from said space between the walls at the other side.

2. In an apparatus of the character described, the combination of a double-walled shell with an annular space between the walls, a plurality of spaced superposed perforated floors within the inner wall, said inner wall having openings at one side above one floor and at the opposite side above the floor next below, and dividing ribs separating the space between the walls at one side from said space between the walls at the other side, the floors extending horizontally through the space between the double walls, and each floor having openings therethrough at one side only.

3. In an apparatus of the character described, the combination of a double-walled shell with an annular space between the walls thereof, a plurality of vertically spaced sets of perforated floors, within the inner wall, each set comprising two superposed spaced perforated floors, the inner wall above the upper floor of one floor set having openings at one side, the inner wall above the upper floor of a floor set next below having openings at the opposite side, and the inner wall at a point between the two floors of the last mentioned set having openings therethrough at the first mentioned side, means dividing the annular space between the two said opposite sides, and horizontal stop means in said annular space at the level of the lower floor of the last mentioned floor set and

at the first mentioned side of said annular space.

4. In an apparatus of the character described, the combination of a double-walled shell with an annular space between the walls thereof, a plurality of vertically spaced sets of perforated floors, within the inner wall, each set comprising two superposed spaced perforated floors, the inner wall above the upper floor of one floor set having openings at one side, the inner wall above the upper floor of a floor set next below having openings at the opposite side and the inner wall at a point between the two floors of the last mentioned set having openings therethrough at the first mentioned side, means dividing the annular space between the two said opposite sides, and horizontal stop means in said annular space at the level of the lower floor of the last mentioned floor set and at the first mentioned side of said annular space; the upper perforated floor of each floor set including raised perforated portions of limited area, said perforated portions being at a level above the shell wall openings which are above that floor.

5. In an apparatus of the character described, a shell, a floor across the shell, said floor having a limited raised and perforated area, means to feed liquid and gas up through said perforated floor area, and means for taking off the liquid at a level above the floor but below the level of the raised perforated area.

6. In an apparatus of the character described, a plurality of vertically spaced sets of perforated floors, each set comprising a superposed spaced pair of perforated floors, spaced concentric shell sections between sets of floors, spaced concentric shell sections between the floors of each set, said concentric shell sections forming annular spaces between the floor sets and annular spaces between the floors of each set, division ribs extending between the concentric shell sections dividing said annular spaces into half annular spaces, the inner shell section above an upper floor of one set having openings therethrough communicating with the half annular space above said upper floor of that set, both the floors of said set having openings therethrough communicating with said half annular space, the upper floor of the next floor set below having an opening therethrough communicating with the said half annular space, the inner shell section below said last mentioned floor having openings therethrough communicating with said half annular space, the inner shell section above said last mentioned floor having openings therethrough communicating with the opposite half annular space, and the said last mentioned floor and the corresponding lower floor of its floor set having openings therethrough communicating with said last mentioned half annular space.

7. In an apparatus of the character described, a plurality of vertically spaced sets of perforated floors, each set comprising a superposed spaced pair of perforated floors, spaced concentric shell sections between sets of floors, spaced concentric shell sections between the floors of each set, said concentric shell sections forming annular spaces between the floor sets and annular spaces between the floors of each set, division ribs extending between the concentric shell sections dividing said annular spaces into half annular spaces, the inner shell section above an upper floor of one set having openings therethrough communicating with the half annular space above said upper floor of that set, both the floors of said set having openings therethrough communicating with said half annular space, the upper floor of the next floor set below having an opening therethrough communicating with the said half annular space, the inner shell section below said last mentioned floor having openings therethrough communicating with said half annular space, the inner shell section above said last mentioned floor having openings therethrough communicating with the opposite half annular space, and the said last mentioned floor and the corresponding lower floor of its floor set having openings therethrough communicating with said last mentioned half annular space; the upper floor of each floor set having raised perforated portions, said perforated portions being at an elevation above the said shell openings that are above said floor.
8. In an apparatus of the character described, a plurality of vertically spaced sets of perforated floors, each floor set comprising a lower perforated floor and an upper perforated floor, the upper floor having a part of its surface raised and its perforations being in the raised surface, inner and outer set spacing shell sections between adjacent floor sets, said shell sections being substantially concentric and spaced apart to provide an annular space therebetween, inner and outer floor spacing shell sections between the floors of each set, said shell sections being substantially concentric and spaced apart to provide an annular space therebetween, division ribs dividing said annular spaces into registering half annular spaces, the inner set spacing shell section above one set having openings therethrough at a level below the raised perforated portions of the upper floor of that set communicating with the half annular space at one side of the shell section, both the floors of that set having an opening therethrough registering with the half annular space at that same side of the shell section, the upper floor of the set next below having an opening registering with the half annular space at the same side of the shell section, the inner floor spacing section of said last mentioned set having an opening therethrough

communicating with the half annular space at the same side of the shell section, and the set spacing shell section above said last mentioned floor set having an opening therethrough at a level below the level of the perforated raised portion of the upper floor of that set communicating with the half annular space at the opposite side of the shell section.

9. In an apparatus of the character described, a shell, a floor across the shell, said floor having a raised and perforated area, means to feed liquid and gas up through said perforated floor area, and means for taking off the liquid from the floor at a point below the level of the raised perforated area.

In witness that I claim the foregoing I have hereunto subscribed my name this 28 day of November, 1927.
